CHUCK-OPERATING DEVICE.

SPECIFICATION forming part of Letters Patent No. 694,189, dated February 25, 1902.

Application filed June 20, 1900. Serial No. 20,968. (No model.)

To all whom it may concern:

Be it known that we, JAMES C. POTTER, a citizen of the United States, and JOHN JOHNSTON, a subject of the King of Great Britain, both residing at Pawtucket, in the county of Providence and State of Rhode Island, have invented a new and useful Improvement in Chuck-Operating Devices, of which the following is a specification.

This invention has reference to an improvement in shipper-operating mechanism, and is particularly applicable to and designed for operating a lathe-chuck in which the dogs or jaws are actuated by means of longitudinally moving rack-bars similar to the lathe-chuck shown and described in United States Patent No. 635,976, of October 31, 1899, for lathe-chucks.

The invention consists in the peculiar and novel construction and the combination of the parts whereby a rock-shaft actuates levers engaging with the shipper-sleeve, as will be more fully set forth hereinafter.

The object of the invention is to operate the shipper-sleeve and the parts connected therewith with increased force and secure greater clamping power in the chuck, clutch, or similar device to which the invention is applied.

In the drawings we have shown the shipper mechanism applied to a lathe-chuck constructed in accordance with the invention shown and described in United States Patent No. 635,976, granted to us October 31, 1899.

Figure 1 is a side view of a lathe-chuck provided with our improved operating mechanism. Fig. 2 is a front view of the lathe-chuck and actuating mechanism, shown partly in section.

In the drawings, a indicates the bed of a lathe; a' , the head-stock; a^2 , the chuck; a^3 , the shipper-sleeve, and a^4 the peripheral groove on the shipper-sleeve.

In Fig. 1 the shipper-sleeve a^3 and groove a^4 , as well as the operating mechanism, are shown in solid lines in the operative position, when the dogs a^5 a^6 of the chuck hold the work or part inserted between the dogs and in broken lines when the dogs are released. The usual means of operating the shipper-sleeve

used heretofore consisted of a bifurcated lever pivoted on a fixed part of the machine and extending transversely to the axial center of the chuck-arbor. Such a lever obstructs the necessary free passage along the side of the machine and cannot under the usual conditions be used of a length to increase the leverage or the power exerted.

When our operating mechanism is applied to a lathe-chuck, we secure in the preferred form the bed b , provided with the brackets b' at the opposite ends, to the bolster b^2 and rigidly clamp the same to the opposite sides of the bed a by screws connecting the clamp-bar b^3 with the bolster b^2 . The shaft b^4 is supported in suitable journal-bearings on the bed b and has near the opposite end bearings the pinions b^5 b^6 , secured to the shaft. On the operative side of the lathe the hand-lever b^6 , having the bracket b^7 extending from the boss of the hand-lever, is secured to the shaft b^4 . On the two brackets b' the levers b^8 b^9 are pivotally supported. These levers are provided at their lower ends with the segmental gears b^9 , which engage with the pinions b^5 b^6 on the shaft b^4 . The levers b^8 b^9 have pivotally connected with their upper ends the shoes b^{10} b^{10} , which enter into the groove a^4 on the shipper-sleeve a^3 at the opposite sides. The stop-pin c , having an enlarged head at the inner end, is placed into the hole c' in the bed b , in which the coiled spring c^2 bears against the head of the pin c . The follower c^3 , in which the stop-pin c moves with a sliding fit, is screwed into the screw-threaded portion of the bed b surrounding the hole c' and retains the stop-pin c in the path of the bracket b^7 ; but the pin c may be pushed inward against the spring c^2 to allow the bracket b^7 to pass by the stop-pin.

In using our improved chuck-operative mechanism the operator, standing usually on the side of the lathe on which the hand-lever b^6 is located, has this lever within convenient reach, while the hand-lever does not obstruct the free passage of the operator to the driving-pulleys, usually at the end of the head-stock. With the parts in the positions shown in solid lines in the drawings, with the work

clamped between the jaws, the operator to release the work moves the hand-lever into the position shown in broken lines, thereby rocking the shaft b^4 and bringing the bracket b^7 in contact with the stop-pin c .

When for the purpose of the adjustment of the dogs the shipper-sleeve and parts connected therewith—such as the rack-bars of United States Patent No. 635,976, above referred to—are required to be moved farther back, the stop-pin c is pushed in to allow the bracket to pass by the same. With the parts constructed in the proportions shown in the drawings the power exerted on the hand-lever is multiplied about ten times and is exerted with tenfold force on the shipper-sleeve and the parts connected therewith. A clutch or chuck or similar devices, such as are used to connect and disconnect pulleys, may be operated by our improved mechanism and the shipper-sleeve while running with increased power.

Having thus described our invention, we claim as new and desire to secure by Letters Patent—

1. In a mechanism for operating a chuck, clutch or similar device, the combination with a shipper-sleeve, of a rock-shaft, pinions on the rock-shaft, and a hand-lever on the rock-shaft, of levers having segmental gears on one end, connecting with the pinions on the rock-shaft, and shoes engaging with the shipper-sleeve on the other end, as described.

2. In a chuck-operating mechanism, the combination with the shipper-sleeve, of a rock-shaft extending transversely to the shipper-sleeve, a pinion on the rock-shaft, and a lever actuated by the pinions on the rock-shaft and connected with the shipper-sleeve, as described.

3. In a chuck-operating mechanism, the combination with the shipper-sleeve, of a rock-shaft, a hand-lever on the rock-shaft, levers connected with the opposite sides of the shipper-sleeve pivoted on a fixed part of the machine, and mechanism for operating the levers through the rock-shaft, as described.

4. In combination with the shipper-sleeve on the chuck, of a shaft extending transversely to the shipper-sleeve, levers supported on fixed bearings on each side of the shipper-sleeve, connections between the levers and the shipper-sleeve, means for operating the shaft, and mechanism connecting the shaft with the levers, whereby the power ex-

erted to rock the shaft is transmitted with increased force to the shipper-sleeve, as described.

5. In a lathe-chuck, the combination of the following instrumentalities: a shipper-sleeve, levers pivotally supported on fixed bearings on each side of the shipper-sleeve, shoes engaging with the shipper-sleeve pivotally supported on the levers, segmental gears on the levers, a transversely-extending shaft, pinions on the shaft, a hand-lever on one end of the shaft, a bracket on the hand-lever, and a stop-pin; whereby the force exerted on the hand-lever is transmitted to operate the chuck.

6. In a lathe-chuck, the combination with the frame of the lathe and the shipper-sleeve on the chuck, of the bed b , the stop-pins c in the bed, and the brackets b' on the bed, of the shaft b^4 journaled in bearings on the bed b , the pinions b^5 on the shaft b^4 , the levers b^8 pivotally supported on the brackets b' , the shoes b^{10} pivoted to the levers b^8 , the segmental gears on the levers b^8 in engagement with the pinions b^5 , and the hand-lever b^6 having the bracket b^7 , as described.

7. In a chuck-operating mechanism, the combination of jaws, racks and pinions for operating said jaws, a shipper-sleeve to which said racks are connected, a lever having one end in engagement with said shipper-sleeve and having on its other end a segment, a pinion engaging said segment and mounted on a fixed journal and having a lever by which it can be revolved, substantially as and for the purpose described.

8. In a chuck-operating mechanism, the combination of a lever mounted on a fixed pivot, connections between said lever and the chuck-jaws, whereby the latter can be operated when the lever is moved between certain limits, said connections being disconnected by a further movement of the lever, and a stop for confining the lever to said first-mentioned limits, substantially as and for the purpose described.

In testimony whereof we have signed our names to this specification in the presence of two subscribing witnesses.

JAMES C. POTTER.
JOHN JOHNSTON.
